ELECTRICAL CONNECTOR RECEPTACLE COMPONENT

Elliott Goldbaum, Brooklyn, and Gordon L. Ablett, New York, N.Y., assignors to Lehigh Valley Industries Inc., New York, N.Y., a corporation of Delaware

Original design applications May 25, 1964, Ser. No. 80,127 and Ser. No. 80,139. Divided and this application Nov. 1, 1965, Ser. No. 87,968

Term of patent 14 years

(Cl. D26—1)

FIG. 1 is a side elevational view of an electrical connector receptacle component, showing one form of our new design with the cover in a closed condition wherein a six-wire system is utilized;

FIG. 2 is an opposite side elevational view of the form shown in FIG. 1 with the cover open;

FIG. 3 is a front elevational view of the form shown in FIG. 1 with the cover closed;

FIG. 4 is a front elevational view of the form shown in FIG. 1 with the cover open;

FIG. 5 is a top plan view of the form shown in FIG. 1;

FIG. 6 is a bottom plan view of the form shown in FIG. 1;

FIG. 7 is a rear elevational view of the form shown in FIG. 1;

FIG. 8 is a side elevational view of an electrical connector receptacle component, showing another form of our new design with the cover closed wherein a seven wire system is utilized;

FIG. 9 is a top plan view of the form shown in FIG. 8;

FIG. 10 is a front elevational view of the form shown in FIG. 8;

FIG. 11 is a front elevational view of the form shown in FIG. 8 with the cover open;

FIG. 12 is a bottom plan view of the form shown in FIG. 8; and

FIG. 13 is a rear elevational view of the form shown in FIG. 8.

This application is a division of each of applicants' prior copending applications, Serial Numbers D. 80,127 and D. 80,139, both filed May 25, 1964, and both abandoned subsequent to filing this application.

We claim:

The ornamental design for an electrical connector receptacle component, as shown and described.
